UNITED STATES PATENT OFFICE

2,506,626

HIGH-FREQUENCY SPOT HEATER

Paul D. Zottu, Indian Hills, Ky., assignor to The Girdler Corporation, Louisville, Ky., a corporation of Delaware

Application May 20, 1944, Serial No. 536,629

10 Claims. (Cl. 219—47)

1
This invention relates to high-frequency systems of the type adapted for the production of heat within dielectric materials and has for an object the provision of a relatively simple, efficient, method and means for producing a substantial amount of heat within a relatively small area.

Though the invention has many applications, it has been found particularly useful in connection with gluing operations of various kinds. Where plywood or other flexible but resilient material is to be adhesively secured to an irregular or curved surface, it has been found advantageous to spot glue the plywood at various points to hold it in shape. Thereafter the glue line as a whole may be dried or hardened.

In carrying out the invention in one form thereof, a high-frequency spot heater comprising a concentric or coaxial circuit is utilized. One end of the coaxial circuit may be conductively connected together while the inner and outer conductors are spaced one from the other at the opposite end to form electrodes. A high-voltage high-frequency electric field is produced between the open, active, end of the spot heater. Thus, when this end is applied to a dielectric material the high-frequency high-voltage field generates heat within the dielectric disposed between the electric field of the inner and outer electrodes. Further in accordance with the invention, provision is made to tune the coaxial line to or near resonance at the desired operating frequency. The tuning means may be either inductive or capacitive, the latter being preferred. Energy is inductively supplied to the coaxial line, provision being made for the adjustment of the coupling between the exciting coil and the coaxial circuit.

Further in accordance with the invention, the coaxial circuit is embodied in a shape which conveniently serves as a hand tool. It may be provided with a pistol grip which extends from the outer conductor, and through which handle or grip both the high-frequency supply line and circuit-controlling conductors may extend.

For a more detailed explanation of the invention, and for further objects and advantages thereof, reference is to be had to the following detailed description taken in conjunction with the accompanying drawings, in which:

Fig. 1 is a sectional elevation of a spot heater;
Fig. 2 is a sectional view taken on the line 2—2 of Fig. 1;

Fig. 3 is a fractional side elevation of a modified form of the invention as applied to a gun of the same type as shown in Fig. 1;

2
Fig. 4 is a fractional side elevation of a modified head comprising the active electrodes;

Fig. 5 is a sectional view taken on the line 5—5 of Fig. 4;

5 Fig. 6 is a sectional view of a further modification of the head, showing a different form of electrodes;

Fig. 7 is an end view of Fig. 6 taken in the direction of the arrows 7—7 of Fig. 6;

10 Fig. 8 is a sectional view taken on the line 8—8 of Fig. 6; and

Fig. 9 diagrammatically illustrates a wiring diagram of a typical system embodying the invention.

15 Referring to the drawings, the spot heater or spotter gun of Fig. 1 comprises a concentric or coaxial circuit having an outer conductor 10 and an inner conductor 11. The inner conductor is supported coaxially of the outer conductor by means of a closure 12 for one end of the outer conductor 10 and a disc 13 of insulating material, such as mica, which at its center supports a bearing member 14. The outer portions of the disc 13 are fastened by screws 14a to lugs 15a of an adapter 15, only two of which lugs are shown in Fig. 1. One end of the inner conductor 11 extends outwardly through the closure 12 and has secured to it an operating knob 16. Supported on a threaded portion 11a of the inner conductor is 20 a movable contact member 17, having a hub 17a which threaded engages the threaded portion 11a. The contact member 17 is provided with a plurality of resilient fingers or contact members 18 which are resiliently biased against the inner surface of the outer conductor 10. It will be observed that the contact member 17 is provided with a slot through which extends a guiding member 20 secured in place as by means of screws 21. The guide member 20 prevents rotation of the contact member 17 when the inner conductor 11 is rotated by means of the knob 16. The hub 17a has extending from it a plurality of contact members or fingers 22 which engage the unthreaded portion 11b of the inner conductor 11.

25 It will thus be seen that the contact member 17, upon rotation of the knob 16 and the inner conductor 11, is moved longitudinally of the coaxial line. Inasmuch as contact member 17 conductively interconnects the outer and inner conductors 10 and 11, the effective length of the coaxial line is varied in accordance with the position of the contact member 17.

It is to be further observed the contact member 17 has the lower section cut away to make room for an exciting coil 23, shown in the form of a

single loop, one end of which is pivotally mounted in a terminal post 24, while the opposite end is carried by an adjusting rod 25 journalled in the closure 12. The end of the rod 25 is provided with a slot 26 for cooperation with any suitable means, such as a screw driver. Also, by means of such a screw driver, a locking set screw 27 may be released and the rod 25 then rotated to rotate the exciting coil 23 to different angular positions, such as shown by the broken lines in Fig. 2.

The forward end of the cylindrical conductor 10 is fastened by means of screws 30 to the adapter 15. The adapter 15 has a peripheral flange 15b which forms a stop or shoulder against which the end of the conductor 10 may abut. The adapter 15 is also provided with a flat plate-like extension 15c through an opening of which the inner conductor 11 extends. The plate 15c forms in combination with a second plate-like member 32 a capacitor. To vary the capacitance the spacing may be varied, and the plate 32 may be cup-shaped, with the outer lip or flange 32a extending parallel to but in spaced relation with the inner surface of the outer conductor 10. The adapter 15 has secured to it an operating head 33. Preferably the head 33 is provided with several, for example three, bayonet slots through one of which there extends the fastening screw 34. A pin may extend through the other bayonet slots (neither of which is shown). The head 33, from the coupling 15, is of conical shape, the sides approaching each other, or the outer wall being of progressively decreasing diameter so as to leave an annular space 35a between the head 33, which with adapter 15 forms an extension of the outer conductor 10, and the end 35 of an electrode, which forms an extension of the inner conductor 11. The electrode 35 is fastened to the end of the inner conductor 11 by means of set screws 36, and extends in spaced relation through the frusto-conical head 33.

From any suitable source, high-voltage high-frequency energy may be supplied to the spot heater by means of a shielded cable transmission line 38. As shown, this cable extends through a bushing 39, of a handle or pistol grip 40, which is secured to the outer conductor 10 by suitable fastening screws (not shown). The inner conductor 41 of the coaxial transmission line, in the form of a cable 38, is electrically connected to the terminal post 24, which is itself mounted upon an insulating member 42. The grounded metallic shield 43 of the cable or line 38 is connected by means of a strap and screw 44 to the outer conductor 10. By means of these connections, the high-frequency energy flows through a circuit including inner conductor 41, the loop 23, the adjusting rod 25, the outer conductor 10, and to the sheath 43. The loop 23 serves inductively to couple the high-frequency energy to the coaxial gun-circuit.

The coaxial gun-circuit or coaxial line itself is tuned to resonance by suitable adjustment of the knob 16. With the coaxial gun-circuit or line tuned to resonance, it forms a tank circuit, having both inductance and capacitance. For a substantial tuning range with substantial changes in the applied frequency, the plate 32, after releasing the set screws, may be moved toward or away from the coupling plate 15c substantially to change the capacitance of the coaxial gun-circuit. For smaller changes, axial movement of the member 17 has the effect of changing the inductance of the line. As shown, the coaxial or concentric line provides a resonant circuit of high efficiency,

or of high Q; that is, the ratio of the capacitive reactance to the resistance is very high, of the order of several hundred.

During normal operation, there is produced within the coaxial line or tank circuit circulation of energy in substantial amounts. The result is the production in the annular space 35a of a high-voltage high-frequency electric field which may be used for heating purposes. It is only necessary to take the spot heater by the handle 40 and apply the active end 33-35 of the concentric line to the material to be heated. After a few seconds, the high-frequency high-voltage electric field established through the material to be heated and between the coplanar outer ends of conductors 33 and 35 will greatly elevate the temperature of most dielectric materials. For drying, activating, or polymerizing adhesives, the spot heater has been found particularly effective.

Further in accordance with the invention, a control circuit 50 is introduced through the handle 40 and by means of a normally open switch 51 the application of the high-frequency energy may be controlled. The switch 51 is operatively connected to a trigger or push button 52. Upon the application of pressure to the trigger or button 52, the switch 51 is closed and as will be described hereinafter, produces operation of the high-frequency generator to supply the spot heater with energy.

As shown in Fig. 1, the spot heater comprising the coaxial gun-circuit is preferably made a quarter of an electrical wave length long. By reason of the added capacity, provided by the wall of conductor 10 and the plates 15c and 32, the spot heater is physically shorter than a quarter wave length. The requirement is that the coaxial circuit be at or near resonance at the operating frequency. It is to be understood the spot heater may be made a half wave length long, in which case, both ends may be made identical with the one including the head 33 and both ends may then function in identical manner. In such a case, neither end would be conductively connected and the high-frequency source of supply could be conductively or inductively applied at any selected point along the length of the coaxial line. It is further pointed out that the spot heater when conductively terminated at one end may be of a length equal to any odd number of electrical quarter wavelengths. If not so terminated, its length may be equal to any even number of electrical quarter wavelengths. Such a construction may be desirable where the source of high-frequency energy is to be applied simultaneously to two or more locations a substantial distance from each other.

In the modification of Fig. 3, a plate 55 (corresponding with the plate 32 of Fig. 1) is threadedly mounted on a threaded section 56 of the inner conductor 11 of the concentric line. The plate 55 has resilient fingers 55a which extend to and engage the unthreaded portion of the conductor 11. This provision eliminates the high-frequency resistance due to the threads and provides better electrical contact than may be obtained by the threaded connection. The disc 55 is provided with a notch into which extends an insulated member 57 secured to the outer conductor 10. The cooperation of the notch and the member 57 prevents the disc 55 from turning and insures its movement axially of the line and in spaced relation with the plate 15c of the adapter 15.

The exciting coil or loop 23 functions as above

described, to apply high-frequency energy to the coaxial gun-circuit. This arrangement provides somewhat greater flexibility in that the gun may be tuned to resonance over a greater range of operating frequencies and the required tuning may be readily effected. In this modification, the member 17 may be fastened directly to the closure 12 and to the outer conductor 10.

It will be further observed the active electrode 35 is resiliently mounted in a housing 59 and is urged outwardly by means of a compression spring 60. This resilient mounting is advantageous in that it insures intimate contact of the electrodes to the material being heated and serves to apply pressure to dielectric members being treated.

In the sectional view of Fig. 5, the adapter 15 is shown in more detail. This coupling member makes possible the use of different heads, such for example, as the one shown in Fig. 4. In this instance, the central electrode 61 is of substantially larger diameter than the electrode 35 of Fig. 3. The outer conductor 62 is provided with any desired opening so that the annular space 63 may be selected or adjusted to meet the needs of the desired heat pattern. In each case, the adapter 15 of Fig. 5 and the head 62 of Fig. 4, both of conducting material, provide a continuation of the outer conductor 10.

Other forms of heads may be utilized, such for example, as the one shown in Fig. 6. In this instance, the outer conductor 62 is cylindrical and of the same diameter as the conductor 10. In Figs. 3, 4 and 6, the length of each head is approximately the same, that is, the length from the adapter 15 to the end of each head. The modification of Fig. 6 includes seven inner electrodes 63, each of which is located in spaced relation with openings 64 in an end plate 65, secured to the conductor 62 as by the screws 66. The respective inner electrodes 63 are mounted on an insulated disc 79 with electrical conductors 71 extending from each electrode 63 to the tubular conductor 72 which is fastened to the inner conductor 11, Figs. 6, 7 and 8.

Though any suitable oscillator may be utilized, the oscillator or high-frequency generator illustrated in Fig. 9 has been found to be satisfactory. Preferably it comprises a push-pull oscillator. As shown, two electric valves 80 and 81 may be mounted within the same envelope 82. This double valve arrangement may be a Number 829 tube, or one of like character. Obviously, each tube or valve may be contained within its own envelope or several valves may be connected in parallel in each side of the push-pull amplifier, these modifications being well understood by those skilled in the art.

It will be observed the respective anodes are connected to the opposite ends 83 and 84 of a loop or coil 85 which at its electrical midpoint is connected by the conductor 86 to the positive source of anode potential as indicated at B+. In accordance with the invention, the positive source of supply is connected directly to ground as indicated at G. This provision is desirable to minimize personnel hazards. A second coil 87 in the form of a single loop is mounted adjacent to and in inductive relation with the coil 85. The respective ends of the coil 87 are connected to the grids of the valves 80 and 81, with the electrical midpoint of coil 87 connected by conductor 88 through a resistor 90 and a shunting condenser 91 to the indirectly heated cathodes of the valves 80 and 81. It will also be

observed the negative side of the source of anode supply is also connected to the cathodes as indicated at B-.

The loop or coil 85 plus the tube capacities plus the distributed capacitance forms a tank circuit of relatively high efficiency and high Q. High-frequency energy is derived therefrom through a conductive connection, including a conductor 93 which is the inner conductor of the coaxial cable 38 previously referred to and which leads to the gun or the spot heater.

This spot heater is diagrammatically shown in Fig. 9 with the trigger 53 arranged to close a circuit for a relay 95 connected in series with a source of supply 96. When the trigger 53 closes this circuit, the relay 95 serves to close the primary circuit for the B supply indicated at 97. The B supply is derived from any available source such as the usual 110 volt, 60 cycle A. C. supply. The supply terminals are indicated at 98 and 99 whereas the B supply or anode current indicated on the box 97 as B+ and B- corresponds with the similar terminals designated in like manner on the left-hand side of the diagram. Whenever the pressure is removed from the trigger 53 the source of anode supply is de-energized by the opening of the relay 95 and when pressure is applied thereto, the relay 95 closes to energize the oscillator.

In accordance with the invention, the oscillator may be designed to produce high-frequency energy of any desired frequency. Frequencies ranging from 150 to 200 megacycles, with a radio frequency output of 75 watts have been found satisfactory for a wide variety of applications of the spot heater.

Common to the several embodiments of the invention is the provision of the concentric circuit which in itself provides a tank circuit of high efficiency.

In a typical embodiment of the invention, with energy applied having a frequency of 150 to 200 megacycles, the outer conductor 10 had a length of 6 $\frac{1}{8}$ " and an overall length from the conductively closed end of the line to the end of the electrode 35 of approximately 9". In this embodiment of the invention, the outer conductor 10 had an outer diameter of 2.125" and an inner diameter of 1.959". The inner conductor 11 had a diameter of $\frac{3}{16}$ " along the unthreaded portion thereof. In Fig. 1, the threaded portion 11a had a diameter of $\frac{5}{8}$ ". This larger diameter extended approximately half-way of the spot heater. In Fig. 3, the inner conductor had a diameter of $\frac{13}{16}$ " through the unthreaded portion and only a slightly larger diameter for the threaded portion.

While preferred embodiments of the invention have been described, it will be understood that further modifications may be made without departing from the spirit and scope of the invention as set forth in the appended claims.

What is claimed is:

1. A high-frequency spotter gun comprising a barrel forming the outer conductor of a concentric line, a second conductor, means supporting said second conductor within said barrel and in spaced relation therewith to form the inner conductor of said line, one end of said inner conductor lying approximately in the same plane as the corresponding end of said outer conductor for application to the work to be heated, said concentric line forming a resonant circuit for a given operating frequency, an input coil within said outer conductor and inductively coupled to said line, means including a pivotal support for

said coil for varying the coupling of said coil with respect to said line by pivotal movement of said coil within said outer conductor to change its angular relation with respect to said inner conductor, and means for varying the electrical length of said line to produce resonance at a selected operating frequency, thereby to produce between and in the vicinity of the coplanar ends of said line a concentrated radio frequency field.

2. Means for producing a concentrated high-frequency electric field between and in the vicinity of an active inner electrode and a grounded outer electrode, comprising conductors forming a concentric line, corresponding ends of which form said electrodes adapted to be applied to work to be heated, a conductor forming a single loop adjacent the inner conductor of said concentric line and disposed within the outer conductor of said concentric line, means including an insulator for pivotally mounting said loop for movement toward and away from said inner conductor to vary the coupling with said inner conductor, and means operable from the outside of said outer conductor for varying the position and coupling of said loop with respect to said inner conductor.

3. A spot heater comprising means for producing a concentrated high-frequency electric field between and in the vicinity of an active inner electrode and a grounded outer electrode formed by corresponding coplanar ends of conductors forming a concentric line, corresponding ends of which conductors form said electrodes which are adapted to be applied to work to be heated, a plate carried by one of said electrodes and extending adjacent the other of said electrodes to form a capacitor within said line, means operable upon relative rotation of the conductors of said concentric line for varying the capacity of said capacitor thereby to tune said line to resonance for a selected operating frequency, and means for supplying said line with high-frequency energy.

4. A material heater comprising means for producing a concentrated high-frequency electric field between and in the vicinity of an active inner electrode and a grounded outer electrode for heating material in contact with said electrodes, conductors forming a concentric line, corresponding ends of which form said electrodes for application to the material to be heated, a pair of radially extending plates forming a capacitor within said line and spaced from said ends of said electrodes, means operable upon relative rotation of the conductors of said concentric line for varying the capacity of said capacitor by changing the axial spacing of said plates thereby to tune said line to resonance for a selected operating frequency, means including a coupling coil within said outer conductor for inductively supplying said line with high-frequency energy, and means for varying the coupling of said coil with respect to said line.

5. A high-frequency spotter gun comprising a barrel forming the outer conductor of a concentric line, a second conductor, means supporting said second conductor within said barrel in spaced relation therewith to form the inner conductor of said line, said concentric line forming a resonant circuit for a given operating frequency, an operating head formed of an electrically conducting material, means for conductively attaching said head to said barrel and for supporting the same therefrom, conductive means extending from said inner conductor and forming in coop-

eration with the free end of said head the end of said line at which there is concentrated an electric field of high frequency to be applied to material to be heated, coupling means located between said conductors for tuning said concentric line, and means effectively connected to said line providing an external connection to a source of high-frequency electrical energy.

6. A high-frequency spotter gun comprising a barrel forming the outer conductor of a concentric line, a second conductor, means supporting said second conductor within said barrel in spaced relation therewith to form the inner conductor of said line, an operating head of electrically conductive material, cylindrical supporting means for said head carried by one end of said barrel, said head being cylindrical at one end and having a frusto-conical shape from said cylindrical portion to the opposite end thereof, an electrically conductive extension for said inner conductor forming with the open end of said head an end of said concentric line at which there is produced a concentrated electric field of high frequency to be applied to work to be heated, coupling means located between said outer conductor and said second conductor for tuning said line, and means effectively connected to said line providing an external connection to a source of high-frequency electrical energy.

7. A spotter gun employing high-frequency electrical energy comprising a barrel forming the outer conductor of a concentric line, a second conductor, means supporting said second conductor within said barrel and in spaced relation therewith to form the inner conductor of said line, said concentric line forming a resonant circuit for a given operating frequency, means for applying energy to said line, an operating head of electrically conductive material, supporting means for said head carried by one end of said barrel, an electrically conductive extension for said inner conductor forming with the open end of said head at least one extension of said concentric line in which there is produced a concentric electric field of high frequency adapted to be applied to work to be heated, said head and said extension of said inner conductor being removable for the substitution of other extensions and heads of the same length but of differing spacing between each said other extension and the open end of each said other head.

8. Heating apparatus employing high frequency electrical energy including a pair of concentrically spaced electrodes adapted to be applied to the work to be heated, coupling means located between said electrodes for tuning said pair of electrodes, and means effectively connected to said electrodes providing an external connection to a source of said energy.

9. Heating apparatus employing high frequency electrical energy including a pair of concentrically spaced electrodes having terminal portions lying substantially in a plane, coupling means located between said electrodes for tuning said pair of electrodes to resonance at the operating frequency, and means providing an external connection from said electrodes to a source of said energy.

10. A high-frequency spotter gun comprising an outer conductor, a rigid hollow electrode extending axially from said conductor and terminating in an annular tip for engagement with work to be dielectrically heated, an inner conductor forming with said outer conductor a concentric line, a yieldable electrode extending from said inner conductor through said annular con-

ductor for engagement with the work, and plate structure within said line adjustably to tune it to produce an intense high-frequency field in the gap between said electrodes as pressed against the work.
